UNITED STATES PATENT OFFICE

2,264,670

METHOD OF MANUFACTURING PRINTING PLATES

Jack J. Kessler, Chicago, Ill., assignor to United Autographic Register Co., a corporation of Illinois

Application December 23, 1940, Serial No. 371,439

4 Claims. (Cl. 41—25)

This invention relates particularly to a method of manufacturing a printing plate of the kind shown in Lowe Patent No. 2,209,127, and more particularly to an improved method for obtaining accurate registration between the printing plate and its backing plate which serves to attach the plate to a printing press.

Printing plates of the kind shown in the above patent are usually of molded rubber firmly secured to a brass backing plate which may be snapped onto a printing cylinder of a press. Such plates have been found extremely useful in printing continuous-form stationery, books, and the like. In printing continuous-form stationery a series of duplicate plates are made from the same matrix and must be very accurately positioned on the backing plate, with respect to its attaching clips, or otherwise the forms on the printed stationery will not be in register when they are brought into superposed relation, and registration of such forms is very essential to a good product. Registration is frequently tested by forcing a knife blade through the top form on a printed line and the knife must cut the same line on the underlying forms with an extremely small amount of tolerance.

Thus it will be understood that it is necessary to make each rubber plate of the exact same length and it is also necessary to position the rubber plate on the backing plate the exact distance from the clips which are subsequently formed on the backing plate. Also, it is necessary to have the ends, on which the clamping bends are made, perfectly parallel to the lines of printed material to insure both vertical and horizontal alignment. Heretofore an attempt was made to accomplish such alignment by means of actual layout on each plate and was dependent for its accuracy on the skill and good eyesight of the operator.

The primary object of the present invention is to provide an improved method of forming the rubber printing plate on the backing plate so that proper registration and alignment are obtained mechanically, that is from fixed guides, so that special skill is not required to obtain this essential feature. By the present invention a slot is formed in the matrix, the slot is used to position a turned end of the backing plate, the turned end is subsequently removed and a clip formed in mechanical alignment with the opposite end of the plate, and finally the opposite clip is formed in mechanical alignment with the first clip. By following this method, accurate alignment and

positioning is carried through the various transfers without any danger of error.

The invention is illustrated diagrammatically in a preferred embodiment in the accompanying drawing, in which—

Figure 1 is a sectional view showing the type form locked up in a chase between two bearer members; Figure 2, a sectional view showing how the matrix is formed from the type; Figure 3, a side elevational view of the metal backing plate having its end portion turned up to fit into the slotted groove formed in the matrix; Figure 4, a bottom plan view of the backing plate shown in Figure 3; Figure 5, a sectional view showing the rubber molding material and backing plate on the matrix; and Figure 6, a sectional view of the completed plate, showing by dotted lines how the turned end or guide flange of the backing plate is cut off and the clips are formed at the ends of the plate.

In the embodiment illustrated, an area of type 1 is placed between an ordinary bearer member 8 and a special bearer member 9 and locked up between the jaws 10 of a chase. The special bearer member 9 is provided with a groove or slot 11 which is very accurately cut so as to be parallel to the lines of type locked up in the chase. After the type has been locked up, a proof copy is made from the type and whatever adjustments or corrections that are found necessary must be made. Subsequently a straight edge metal insert 12 is inserted in the slot 11 to form an aligning slot or groove in the matrix in the subsequent molding operation. It is preferable to have the member 12 removable so that it will not cut or interfere with the inking roll when proof is being made. As shown in Figure 2, the assembly in Figure 1 is inverted and an impression is made in the matrix 13 which preferably is a thermoplastic material. By the application of heat and pressure the matrix 13 is thus formed and after being properly cured is ready to receive the rubberous molding material 14 and backing plate 15.

The brass backing plate, illustrated in Figures 3 and 4, preferably is a thin brass sheet in the form of a very accurately measured rectangle. One end 16 is turned down to form a positioning flange disposed at 90° to the remainder of the backing plate. A sheet of rubber or rubberous molding material is then placed on the matrix over the type impression and preferably a thin fabric is placed over the rubber sheet. The fabric is coated with a cement on one side which is presented to the backing plate 15 when it is brought into superposed relation with its flange

16 placed in the slot 17 provided in the matrix.

By the application of heat and pressure the rubber is then cured on the matrix and in that operation becomes adhered securely to the backing plate through the medium of the attaching fabric, the rubber flowing into the fabric and the fabric in turn becoming cemented securely to the backing plate. The combined rubber plate and backing plate is then removed from the matrix and the matrix is ready to be used in forming additional identical plates.

It is possible to form one of the attaching clips utilizing the flange, but preferably the backing plate is placed in a shearing machine with its edge 18 in contact with a fixed guide and the flanged portion 16 is sheared off along a line exactly parallel to the edge 18. The plate is then removed to a forming machine where the edge 18 is placed against a mechanical guide and the V-shaped clip 19 is struck from the material on the opposite end. The plate is then reversed and using the clip 19 for a guide, a clip 20 is formed.

As will be readily understood, it is necessary to work between narrow limits in forming the plates. The transversely extending clips 19 and 20 must be exactly parallel and a variation in their spacing of a sixty-fourth of an inch would prevent their proper attachment to a printing roll which subsequently rotates at high speed. If one of the printing plates should become loose while the machine is operating, severe damage to the press might result. However, by practicing the present method, a high degree of accuracy is assured and the cost of producing the plates is greatly reduced.

The foregoing detailed description has been given for clearness of understanding only, and no unnecessary limitations should be understood therefrom for some modifications will be obvious to those skilled in the art.

I claim:

1. The method of registering a printing plate on a backing plate which comprises: forming a matrix with a slot aligned with respect to the type impression in the matrix; placing rubberous molding material on the matrix and superposing a metal rectangular backing plate of proper size having an integrally formed perpendicularly disposed aligning flange extending into the matrix slot; curing the rubberous molding material and simultaneously securing it to the backing plate through the application of heat and pressure; removing the combined printing and backing

plate from the matrix; forming one end of the backing plate into an attaching clip mechanically aligned with respect to the opposite end of the backing plate; and then forming another clip, opposite from the first clip and mechanically aligned with respect thereto.

2. The method as specified in claim 1, including the step of cutting off the aligning flange of the backing plate prior to forming the first clip.

3. The method of registering a printing plate on a backing plate which comprises: locking up type between bearer members in a chase, one of the bearer members having an upwardly extending straight edge portion; forming a matrix on said type and straight edge so that the latter will form an aligning slot in said matrix; placing rubberous molding material on the matrix and superposing a metal rectangular backing plate of proper size having an integrally formed perpendicularly disposed aligning flange extending into the matrix slot; curing the rubberous molding material and simultaneously securing it to the backing plate through the application of heat and pressure; removing the combined printing and backing plate from the matrix; forming one end of the backing plate into an attaching clip mechanically aligned with respect to the opposite end of the backing plate; and then forming another clip, opposite from the first clip and mechanically aligned with respect thereto.

4. The method of registering a rubber printing plate on a backing plate which comprises: locking up the type between bearer members in a chase, one of said bearer members having a slot; placing a thin metal insert in said slot so that said insert extends slightly above the top of the bearer member; forming a matrix against said type and insert; removing said matrix and insert; placing a sheet of rubberous material on said matrix and superposing a backing plate with an aligning flange extending into the slot in the matrix; curing the rubber and securing it to the backing plate by the application of heat and pressure; removing the assembly from the matrix and cutting off the flange portion at a mechanically fixed distance from the opposite edge of the backing plate; forming an attaching clip on the trimmed edge of the plate in mechanical alignment with the opposite edge portion; and forming a clip on the opposite end of the plate at mechanically measured distance from the first clip.

JACK J. KESSLER.
